DISPLAY RACK FOR GREETING CARDS OR SIMILAR ARTICLE

Fred M. Slavic, New Rochelle, N. Y.

Application September 2, 1958, Serial No. 52,461

Term of patent 14 years

(Cl. D80—9)

I claim:

The ornamental design for a display rack for greeting cards or similar article, as shown.
